UNITED STATES PATENT OFFICE.

SAMUEL HELLER, OF NEW YORK, N. Y.

DESIGN FOR A PRECIOUS OR SEMIPRECIOUS OR SYNTHETIC STONE OR AN IMITATION THEREOF.

47,694.

Specification for Design.

Patented Aug. 10, 1915.

Application filed November 12, 1914. Serial No. 871,794. Term of patent 7 years.

To all whom it may concern:

Be it known that I, SAMUEL HELLER, a citizen of the United States, residing in the borough of Manhattan, in the city, county, and State of New York, have invented a new, original, and ornamental Design for a Precious or Semiprecious or Synthetic Stone or an Imitation Thereof, of which the following is a specification, reference being had therein to the accompanying drawings, which form a part thereof.

In the drawings: Figure 1 is a plan view of a cut stone embodying my design; Fig. 2 is a side view thereof; and Fig. 3 is an end view thereof.

I claim:

The ornamental design for a precious, or

semi-precious or synthetic stone or an imitation thereof consisting of a flat table extending across the crown and having at each side thereof and extending at an angle therefrom toward the girdle, a large triangular facet, the base of which is at the table and the apex of which is at the girdle, and a smaller triangular facet at each side thereof, and of a pavilion having facets thereon.

SAMUEL HELLER.
